UNITED STATES PATENT OFFICE.

VICENTE VITA, OF WASHINGTON, DISTRICT OF COLUMBIA.

CRYPTOGRAPHIC APPARATUS.

Application filed August 4, 1927. Serial No. 210,640.

The invention forming the subject matter of this application relates to an instrument for constructing messages in code and for deciphering these messages.

5 The main object of the invention is to provide an instrument composed of a few very simple elements relatively movable to form code word-combinations corresponding to numbers or plain language words, or vice 10 versa, of such great variety as to render it practically impossible for any one to decipher a message without knowing the key number, and for the sake of clarity, there is herein described a code system adapted for 15 use with the said instrument to provide the greatest possible secrecy in the employment of diplomatic and commercial codes.

Other objects of the invention will become 20 apparent as the detailed description thereof proceeds.

In the accompanying drawings,

Figure 1 is a plan view of the instrument; Figure 2 is a vertical section on the line 2—2 of Figure 1; and,

25 Figure 3 is a plan of one of the semi-circular disks of the instrument.

The instrument comprises a base plate 1 having three circular disks or plates 2, 3, and 4 respectively mounted to rotate freely 30 and independently about a common center pin 5. The base plate 1 is provided with index lines *x* and *y* extending radially from the center of pin 5 and adjacent the circumference of the disk 2.

35 The disk 2 is of larger diameter than the disk 3, which, in turn, is larger in diameter than disk 4. Superposed on the disk 4 and pivoted about the pin 5 is a semi-circular plate 6 of substantially the same diameter as disk 4. Between the disks 3 and 4 a semi-circular plate 7 of substantially the same diameter as disk 3 is also pivoted at its center to the pin 5; and a similar semi-circular plate 8, of practically the same diameter 40 as disk 2, is pivotally mounted on pin 5 to rotate between the disks 2 and 3.

The plate 6 is adapted to be clamped in any desired angular position on disk 4 by any suitable means such as the clip 9; and 50 clips 10 and 11 may be used to clamp the plates 7 and 8 in any desired angular positions on the disks 3 and 2 respectively.

55 It must be understood that the instrument itself may be embodied in many different mechanical forms without departing from the principle of the invention, and the par-

ticular embodiment described herein is taken in its simplest form to illustrate the principles of the system. Various other modifications of the instrumental part of the invention will readily suggest themselves to persons skilled in this art, and the claims appended to this specification are intended to cover such modifications in their broadest aspects.

60 The code system proper, for purposes of transmission, is such that five code letters or figures represent a complete word. Accordingly, the letters and figures on the several disks and plates of the instrument are 65 arranged so as to be read in groups of five letters or five figures to be read in lines coincident with a line joining the index lines *x* and *y*.

70 For convenience of description, and illustration the numbers on the several plates 6, 7, and 8 are read with reference to the line *x*, which may therefore be considered as the figures or number indicator; while the letters on the underlying disks 2, 3, and 4, are 75 read with reference to the index line *y* which may therefore be considered as the letters or word indicator.

75 In the particular embodiment of the invention shown in the drawing there are one hundred equi-angularly spaced radial lines 12, drawn on each of the semi-circular plates 6, 7, and 8; and numbers 13 are inscribed on each line. The numbers and lines on the plates 6, 7, and 8 are arranged between the 80 outer arcuate edges of the plates and semi-circular lines 14, 15 and 16 on the respective plates 6, 7, and 8; and, in effect, constitute substantially semi-annular numerical scales, 85 each of which has one hundred divisions or graduations. For convenience of description, these numeral scales are designated by the reference characters 17, 18 and 19 respectively, and each numbered from 00 to 99.

90 On the circular disks 2, 3, and 4, immediately below the plates 6, 7, and 8, the letter scales 19, 20 and 21 are inscribed. The letter scales 19 and 20 are formed between the circular edges of disks 2, 3, and 4, and the scale 21 is inscribed between the edges 95 of disk 4 and a circle 22 drawn on disk 4. Each of the letter scales comprises, in this case, two hundred equiangularly spaced radial lines 23, and therefore, have the same angular spacing as have the lines 12 on the 100 semi-circular plates 6, 7, and 8.

110 In the various forms of this invention it

is intended that the plates 6, 7 and 8, or their equivalents shall be divided by one hundred equiangularly spaced radial lines, and that the lettered elements will be divided in multiples of one hundred. For example, the circular disks may be divided into four hundred equiangularly spaced radial divisions; and, since each division on the numbered plates must be equal to a division on the lettered disks, it follows that the numbered plates must be substantially quadrants of a circle. Division of the circular disks into six hundred spaces, would require number plates shaped as sectors, each comprising one-sixth of a circle. In other words, the size of the numbered plates is inversely proportional to the number in hundreds of the divisions on the lettered disks.

20 Where the disks are divided into one hundred parts only, the numbered plates will obviously be complete circles, and the numbered scales must be offset laterally relative to the letter scales in order that the 25 latter may be read.

In the operation of this system, the operators must agree to use:—

(1) A particular code, dictionary commercial code, or any other book containing the 30 words necessary for communication;

(2) A secret number of five figures ranging from 00000 to 99999;

(3) They must agree upon the position in a telegram or letter, sent from the message 35 sender to the receiver, of a ciphered or code word corresponding to the secret number.

When the message is received, the receiving operator rotates the number plates until the five figures forming the secret number, are alined with the number index α ; and then, keeping these plates so positioned, rotates the lettered disks until the five lettered code word corresponding to the secret 40 number is alined with the word index y .

45 In this position, the numbered plates are fastened to the respective lettered disks so that each disk and the plate fastened thereto rotate independently of the other disks and plates.

50 When the parts of the instrument are set up as just described, the receiving operator takes the first cypher word in the telegram or message, and rotates the disks, with the number plates fastened thereto, in one direction or another until the five letters of the word appear alined with the letter index y . This operation brings five figures of the number plates into alinement with the 55 number index α from which the plain language word corresponding to the code word may be determined.

In the use of numbers to determine the location of a word in the book agreed upon, any convenient system may be followed; for example, the first three numbers may re-

fer to the page of the book and the last two numbers may refer to the location of the word on the page, counting from the top or bottom or other location as agreed upon.

The device may also be used independently 70 of any book or key numbers, by providing the numbered disks with a series of letters 24, which may be used independently of the numbers to form words in a manner which will be obvious to persons skilled in 75 the art.

The essential part of this system involves the adjustment of the numbered plates over the lettered disks immediately below each of them, and the fixing of these plates to these 80 disks for decoding purposes.

I claim:—

1. A code instrument comprising a support; three annular members rotatable about a common center on said support, each 85 having a series of equiangularly spaced lettered radial lines inscribed thereon, and three semi-annular members rotatable on said support about the same center, each having a series of equiangularly spaced 90 numbered lines inscribed thereon, the angular spacing between the numbered lines on the second named members being equal to the angular spacing between the lettered lines on the first named members. 95

2. A code instrument comprising a support; three annular members rotatable about a common center on said support, each having a series of equiangularly spaced lettered radial lines inscribed thereon, and three semi-annular members rotatable on said support about the same center, each having a series of equiangularly spaced numbered lines inscribed thereon, the angular spacing between the numbered lines on the second named members being equal to the angular spacing between the lettered lines on the first named members, and means 100 for securing each of said numbered members to one of said lettered members. 105

3. A code instrument including a base plate, a circular disk rotatably mounted thereon, and having an annular series of equiangularly spaced lettered radial lines thereon; a semi-circular plate of the same 115 diameter as said disk and having a semi-annular series of equi-angularly spaced numbered radial lines inscribed thereon; said plate being superposed on said disk and rotatable independently thereof about the same center; and means for securing said plate in any desired position on said disk. 120

4. A code instrument comprising a base plate; a circular disk rotatable about on 125 said base plate; a semi-circular plate of the same diameter as said disk and superposed thereon to rotate independently about the same center; a second circular disk of smaller diameter than the first named disk 130

and superposed on said plate and first named disk to rotate independently thereof about the same center; and a second semi-circular plate of the same diameter as said second disk superposed on the said second disk to rotate independently thereof about the same center, and adjustable means for securing each of said plates to the disk immediately below it; said disks and plates being provided with cooperative coding indicia.

5. The combination with the instrument set forth in claim 4 of a third circular disk superposed rotatably about the same center 15 on the second named plate and disk; and a third semi-circular plate, of the same diameter as the third disk and smaller than each of the other disks, superposed rotatably about the same center, on the said third 20 disk; each disk being provided with an annular series of equiangularly spaced lettered radial lines adapted to aline with the radial lines on the other disks; and each semi-circular plate being provided with a semi- 25 annular series of equiangularly spaced num-

bered radial lines, adapted to aline with the radial lines on the other disks and plates; and said base plate being provided with a radial index line for said numbered lines, and with a second index line for the 30 lettered lines on said disks.

6. A code instrument including a support having index marks thereon; relatively movable members each having a series of lettered indicia inscribed thereon; relatively movable elements arranged movably in alternation with said members and having numbered indicia inscribed thereon; the indicia on all of said members and elements being equidistantly spaced from each other 40 and adapted to be adjusted into alinement with each other and with said marks.

7. The combination with the instrument set forth in claim 6 of means for securing each of said elements to one of the members 45 adjacent thereto.

In testimony whereof I affix my signature.

VICENTE VITA.
